H. D. WHIPPLE.
REINFORCED CONCRETE RETAINING WALL.
APPLICATION FILED SEPT. 25, 1912.

1,058,211.

Patented Apr. 8, 1913.

UNITED STATES PATENT OFFICE.

HENRY D. WHIPPLE, OF BROOKLYN, NEW YORK.

REINFORCED-CONCRETE RETAINING-WALL.

1,058,211.

Specification of Letters Patent.

Patented Apr. 8, 1913.

Application filed September 25, 1912. Serial No. 722,340.

To all whom it may concern:

Be it known that I, HENRY D. WHIPPLE, a citizen of the United States of America, residing at Brooklyn, in the county of Kings 5 and State of New York, have invented certain new and useful Improvements in Reinforced-Concrete Retaining-Walls, of which the following is a specification.

This invention relates to certain new and 10 useful improvements in concrete bulkheads or retaining walls; the object being to provide a sectional retaining wall formed of a plurality of piling units so constructed that they can be readily driven into position or 15 sunk by the method now in use, whereby an exceedingly strong and durable wall will be formed, and one which is especially adapted to be used for forming a protection for levees, in order to form a sectional core for 20 the levee to prevent craw-fish from working transversely through the levee.

Another object of my invention is to provide a sectional reinforcing wall in which each of the piling units is formed of a member having an obliquely cut-off beveled penetrating end which can be readily driven into position, and one which will clean its way as it is forced down into position against the adjacent unit whereby an exceedingly 30 tight joint is formed between the units; said units being staggeredly arranged in order to form lap-joints; the crevices of 35 which will soon become filled with the earth or sand in which they are driven in order to form a water-tight wall.

A still further object of the invention is to provide a sectional reinforced retaining wall, which can be used for forming jetties, breakwaters, sea walls, dams, and for various other purposes; each section of the wall 40 constituting a piling unit with a reinforced or metal penetrating point in order to prevent the concrete from chipping when brought into engagement with an obstruction.

Other and further objects and advantages of the invention will be hereinafter set forth and the novel features thereof defined by the appended claims.

In the drawing—Figure 1, is a perspective 50 view of a retaining wall constructed in accordance with my invention, showing the application of the same to a levee; Fig. 2, is a longitudinal horizontal section through 55 the same, showing the manner of arranging the sections in respect to each other in order to form lap-joints; Fig. 3, is an end eleva-

tion partly in section; Fig. 4, is a vertical longitudinal section of a portion of one of the piling units; Fig. 5, is a detail perspective of the starter and one of the units, showing the manner of forcing the unit into position; and Fig. 6, is a detail perspective view of the pointed ends of a series of piling units.

Like numerals of reference, refer to like parts in the several figures of the drawings.

In carrying out my invention, I employ a plurality of right and left piling units 1 and 2, which are formed rectangular in 70 cross-section having a metal reinforcement 3 preferably formed of electrically welded wire mesh arranged, as clearly shown in Fig. 4. These units can be molded in an ordinary concrete mold, and can be formed 75 of any size desired, and I preferably construct the units in the form of a slab with its lower end beveled and cut-off obliquely, as shown at 4, in order to form a penetrating 80 point which will force the unit laterally and longitudinally against the adjacent unit, as the same is forced into position so as to form a tight joint; said penetrating point cleaning the abutting surfaces 85 of the adjacent units as it is forced downwardly by the peculiar shape of the penetrating point.

In order to protect the penetrating point when working in rocky countries, I provide a galvanized metal cap 5 having its lower 90 end cut-off obliquely and beveled conforming in shape to the penetrating point of the piling unit, and preferably secured in position by transverse rivets, as shown at 6.

These caps are preferably counter sunk 95 in the units in order to obtain a flush face upon all sides, so that when the units are arranged in position, as shown, they will fit snugly against each other. The great trouble in forming concrete retaining walls 100 of this nature, now in use, is in handling the material or the units constituting the retaining wall, and I have found that by constructing the units the shape shown, an exceedingly strong and durable retaining 105 wall is formed and one which can be constructed at a very low cost as the units can be molded as the wall progresses, and handled without the use of expensive machinery.

I am aware that I am not the first to provide a retaining wall of piling units, but the walls hereinbefore constructed have not proved successful so far as I am aware as

in sinking the units it was impossible to maintain the close relation of the units that is essential in forming a retaining wall, while with my construction of penetrating 5 point, the units are forced together as they are sunk into position.

In constructing a retaining wall of a plurality of units, as hereinbefore described, a starter 10 constructed substantially the same 10 as the units with the exception of a vertical shoulder 11, is first sunk into position and a left unit is placed against the same and sunk into position, and then a right unit is placed upon the opposite side and sunk into position, this being carried out until the desired 15 length of wall is formed; the right and left units being staggeredly arranged so that a lap-joint is formed, and it will be seen that as the unit is forced downwardly into the 20 corner formed by a pair of the transversely sunk units, the chiseled point will clean the earth out of the corner as it is forced downwardly, allowing the units to be set tightly 25 against each other; the peculiar shape of the point forcing the unit being sunk tightly into the corner and against the adjacent units, which is the essential feature of my invention, as I have found that unless a piling unit has a point which will force the 30 unit in two directions, as it is forced into ground, it is impossible to construct a retaining wall of a plurality of units which will be practically water-tight, as the units will sheer off to one side and will not maintain 35 their close relation to each other, as is necessary.

It will be seen that by arranging the units in a staggered manner, the point, for instance of the right unit, will be at the center 40 of the left unit, or vice versa, allowing the earth to be compressed or forced aside as the units are sunk into position.

In order to strengthen the top of the units and to maintain the same in their proper 45 position, I provide a cap 7 formed of reinforced concrete which is also formed of sections; the reinforcement employed being of electrically welded wire mesh, as shown at 8. The upper ends of the piling units are 50 preferably secured together by transverse bolts 9, passing through registering openings formed in the units as shown, and while I have only shown a single cap unit, it is of course understood that these caps are to be 55 formed of such a size that they can be handled readily, or they can be molded over the units, and it is not essential that they be secured in position, as they will maintain their proper positions upon the piling units 60 by their own weight and shape, as they straddle the top of the units which is clearly shown in the perspective view and the horizontal section.

From the foregoing description, it will be seen that I have provided a sectional reinforced concrete retaining wall, which is formed of a plurality of right and left units staggeredly arranged in order to form lap-joints said units having penetrating points which force the unit as the same is being sunk in two directions, in order to form a compact wall when completed, which will have all of the advantages of a solid wall.

In the specification I have used the terms "right and left units" which is to define 75 that units are used in which the penetrating points of one set of units are beveled reverse to the bevel portion of the other set of penetrating points which is essential in the construction of my retaining wall.

I claim:

1. A reinforced concrete retaining wall formed of a plurality of staggeredly arranged piling units having oppositely obliquely cut-off beveled penetrating points.

2. A reinforced concrete retaining wall formed of a plurality of piling units staggeredly arranged, each unit having an obliquely cut-off beveled penetrating point, the bevel of the points of the right units being 90 reverse to the bevel of the points of the left units.

3. A sectional reinforced concrete retaining wall formed of a plurality of piling units each unit having an obliquely cut-off 95 beveled penetrating point, said units being staggeredly arranged, and a cap arranged over the top of said units.

4. A piling unit for retaining walls, comprising a reinforced concrete member substantially rectangular in cross section having a cap at its lower end formed of galvanized metal cut-off obliquely and beveled.

5. A sectional reinforced concrete retaining wall having smooth side faces, said wall 105 being formed of parallel rows of abutting piling units staggeredly arranged, each piling unit having its lower end cut-off obliquely and beveled, and a cap arranged over said units and secured in position thereon.

6. A sectional reinforced concrete retaining wall formed of a plurality of piling units staggeredly arranged side by side, each unit having a penetrating point cut off obliquely and beveled for forcing the same longitudinally and laterally in position against the adjacent units, the bevel of the points of one set of units being reverse to the bevel of the points of the other set of units.

In testimony whereof I affix my signature in presence of two witnesses.

HENRY D. WHIPPLE.
